UNITED STATES PATENT OFFICE.

ALBERT EDWARDS, OF NEW YORK, N. Y.

IMPLEMENT FOR WASHING CLOTHES.

1,184,838.

Specification of Letters Patent. Patented May 30, 1916.

Application filed July 16, 1915. Serial No. 40,258.

To all whom it may concern:

Be it known that I, ALBERT EDWARDS, a citizen of the United States, and a resident of the borough of Brooklyn, city and State of New York, have invented certain new and useful Improvements in Implements for Washing Clothes, of which the following is a specification.

The invention relates to devices for washing clothes, and has for some of its objects to provide such a device which can be easily and cheaply manufactured, which shall be simple in construction and effective in operation, and which can be easily operated.

The invention consists in the novel construction, arrangement, and combination of elements and parts, as shown in the accompanying drawings and fully described in this specification.

In the said drawings, Figure 1 is a side view of my invention; Fig. 2 is an end view on an enlarged scale, as seen from the left of Fig. 1; and Fig. 3 is a section of a portion 25 of my invention, taken on the line 3—3 of Fig. 2 and on the same scale.

In carrying my invention into effect in the embodiment which I have selected for illustration in the accompanying drawings and description in this specification, I provide a suitable handle 11, preferably of waterproof material, or of wood or the like suitably coated. Attached to one end of this handle is a member 12, of soft rubber or some other flexible and elastic substance, which is normally of the shape shown (in side view) in Fig. 1, that is, somewhat resembling a cone or pyramid, with an open base, and the handle 11 extending from the apex. It is preferable, although not absolutely essential, that this member have a polygonal cross-section, as shown, for instance in Fig. 2, for a purpose to be herein-after set forth.

The member 12 is reinforced, near the point of attachment of the handle 11, with a number of internal ribs 13, as shown in Fig. 2. The member 12 is also provided with a number of projections 14 and 15 at various points on its inner surface, and it will be seen by reference to Fig. 3, that some of these knobs or projections are longer than others.

In operation the device is repeatedly

forced downward to its full extent in the 55 tub or other receptacle containing clothes to be washed. The manner in which it performs its function will now be described. At the beginning of each downward stroke, the member 12 is full of water, and lightly 60 resting upon the clothes in the tub. As it is forced downward, the first effect is to compress the clothes immediately thereunder and to force through the said clothes the water inside the member 12. As the downward 65 stroke is continued, the member 12 flattens out upon the clothes, the knobs 14 and 15 rubbing against them as they move outward in a direction approximately at right angles to the movement of the handle 11. The 70 member 12 continues to be flattened out as far as the ribs 13 will permit, and at the end of the downward stroke turns partially inside out. It will be observed that by providing a member 12 shaped as shown in the 75 drawings, this flattening movement is greatly facilitated, as in order to produce a flat surface from this member 12 it is only necessary to flatten out the various folds, (which I have designated 16.)

As the member 12 is flattened out and moves over the clothes, the knobs 14 and 15, as stated above, rub against them. The longer knobs, designated 15, are bent inward by the friction of the clothes, so that they 85 are dragged over the clothes by the outward movement of the member 12. Upon the end of the downward stroke, and the commencement of the upward one, the pressure on the member 12 is released, and it tends to resume its former shape, as rapidly as the upward movement of the handle will permit. The inwardly bent knobs 15 then act as hooks, dragging the clothes into the interior of the member 12, and, when the upward 90 stroke is continued, pulling them upward and dragging them over other clothes for a short distance before they drop free from the member 12. In the course of the upward stroke, a certain amount of water is 100 sucked through the clothes into the interior of the member 12, and at the end of said stroke the member 12 is again full of water.

The advantages of my invention will be obvious from what has been above set forth 105 with regard to its construction and mode of operation. It will be seen that the simple up and down movement of the handle 11 is

transformed into a variety of movements which all combine to thoroughly cleanse the clothes in the tub.

Having thus described my invention, what I claim as new and desire to secure by Letters Patent is as follows:

- 5 1. A device of the character described comprising a hollow flexible member adapted to be spread out when pressure is applied thereto, and provided with internally projecting studs adapted to exert sidewise friction as said member is spread out.
- 10 2. A device of the character described comprising a hollow flexible member adapted to be spread out when pressure is applied thereto, and provided with internally projecting studs, some of said studs being of different length from others; said studs being adapted to exert sidewise friction as

said member is spread out, and certain of 20 said studs being adapted to act as hooks as said member resumes its normal position.

3. A device of the character described comprising a hollow flexible member having a polygonal cross section and an apex, and 25 adapted to be spread out by pressure upon said apex.

4. A device of the character described comprising a hollow flexible member having a polygonal cross section and an apex, 30 provided with internal reinforcing means and with internally projecting studs, and adapted to be flattened out by pressure upon said apex.

In witness whereof I have hereunto signed 35 my name this 14th day of July 1915.

ALBERT EDWARDS.
